UNITED STATES PATENT OFFICE.

TANNY C. GUSEMAN, OF HOUSTON, TEXAS.

STITCHING-MACHINE GUARD.

Application filed January 10, 1921. Serial No. 436,281.

To all whom it may concern:

Be it known that I, TANNY C. GUSEMAN, a citizen of the United States, residing at Houston, Harris County, Texas, have invented a certain new and useful Improvement in Stitching-Machine Guards, of which the following is a full, clear, and exact description, such as will enable others skilled in the art to which it appertains to make and use the same.

My invention relates to stitching machine guards for use in protecting the uppers of shoes from contact with the operating parts of a sole stitching machine. It is designed particularly for use on the machine commonly known as the Goodyear outsole rapid lockstitch machine. It is an improvement on the design of guard shown and described in Patent to Ashworth, Serial No. 1,253,831, issued January 15, 1918.

In stitching soles on shoes, a common type of machine used employs a curved needle and awl which, in the sewing operation, come close to the upper and, unless great care and skill are employed, the upper will be pierced or torn by them so as to injure the shoes. Further, the looper and take-up will come into contact with the shoe upper and smear the same with wax or oil.

The common type of guard now employed comprises a thin sheet of spring steel or sheet iron which is secured to a holder attached to the machine between the take-up and the work. It hides the needle, awl, looper and take-up and has to be pivoted so as to be swung out of the way when access to the named parts is desired.

Furthermore, the guard, when thus placed, interferes with the insertion of the sole beneath the needle. Pressure has to be exerted on the shoe to get the sole in position. This pressure brings the upper against the guard and bends the guard inwardly so far that it often interferes with the operation of the looper and awl. The result is that the guard is usually removed by the operator, who prefers to work without it.

The object of my invention is to provide a device to guard the uppers of shoes from injury, in the use of shoe stitching machines, which will not interfere with the working of the machine. It is further desired to so shape and position the device that it will effectually prevent the upper from injury or mutilation and at the same time will not be in the way of the operator.

Another object is to do away with the necessity of a holder for the guard and at the same time provide a simple and strong construction.

Referring to the drawing forming a part of this specification and wherein like parts are designated by like numerals of reference throughout the several views, Fig. 1 is a front elevation showing my guard positioned on a part of a stitching machine and showing broken parts of said machine sufficiently to indicate the operation of my invention; Fig. 2 is a top plan view of my guard; Fig. 3 is a side or edge view thereof, and Figs. 4 and 5 are front and side elevations, respectively, showing a modified form of my invention.

The broken parts of the Goodyear stitching machine shown in the drawing are intended merely to indicate the position of my improved guard relative to the needle and looper and to the adjacent parts. The guard, designated by the numeral 1, comprises a sheet of spring steel or similar resilient material. It is secured by means of screws 3 and 4 to the gage slide 2, which in turn is slidably secured on the frame of the machine. To the upper end of the gage slide 2 is also secured, by means of the screws 3 and 3', the curved edge gage 5. The needle 6, the presser foot 7, and the work table 8 are shown in their relative positions. Below the table are the looper 9 and the take-up lever 10.

The particular construction of the preferred embodiment of my device is shown in the three views. The body of the guard 1 has openings or slots 12 therein to receive the screws 3, and 4, by which it is secured adjustably in place. To hold the plate more firmly I bend the right hand side of the plate rearwardly at 13, as shown in Fig. 2, to fit around the outer side of the edge gage 5. The upper left hand edge is extended laterally and curved slightly outwardly to form a lip 11 resting against the outer end of the table 8. I find that if the guard is positioned immediately to the right and in front of the work table 8 the best results are obtained. I have, therefore, designed the guard to be secured to the gage slide 2 or to the edge gage 5, the object being to secure the resilient guard having the outturned lip 11 resting resiliently against the lower edge of the table 8. The work advances under the pressure foot 7 and between the same and the table 8 in a direction from right to

2
left. I therefore refer to the right side of the machine as the forward side. Placing the lip 11 of the guard in the position as described and shown will throw the upper 5 out away from the needle, awl, and looper far enough so that no contact or injury between the said parts and the upper will take place. One is thus enabled to advance the 10 shoe easily into the desired position and the contact of the upper with the lip of the guard will press it out of the way of the awl and needle until it has passed those parts where it will again assume its usual 15 form and position.

15 It is my object, therefore, to place the outwardly curved lip 11 in the position shown. I have shown the guard on which the lip is formed as extending down for attachment to the gage slide 2. It is obvious, 20 however, that it might be much shorter than shown and I find that it may be secured to the edge gage alone, the idea being to form the lip of resilient material and to position it to bear lightly against the forward end 25 of the table.

In the modification shown in Figs. 4 and 5 there is formed a lip 14 on the forward end of the table 8. This lip as shown is a flat downwardly inclined projection so positioned on the table as to bear against the upper and force it away from the path of the needle and awl and thus prevent injury when the work is being performed.

30 While this embodiment of my invention does 35 not shield the upper from the looper as

effectually as my preferred form, it is simple and strong and not liable to injury.

When thus constructed the needle and looper are accessible at all times. No adjustment of the guard will ordinarily be 40 necessary. When once properly positioned it will need no further attention. It will force the upper out of the path of the working parts of the machine and will yet not interfere with ready access to said parts. 45 Furthermore, it will not itself be pressed against the looper and awl to interfere with their operation.

Having thus described my invention, what I claim as new and desire to protect by Letters Patent is:

In a device of the character described, a 55 stitch-forming mechanism including a table, a presser foot, a needle, a looper, a gage slide and a stationary edge gage, in combination with a guard comprising a sheet of resilient material secured adjustably to said gage slide and fitted along said edge gage in a position spaced to one side of said looper and needle, a laterally extending 60 lip on said guard, the upper edge thereof being on a level with the top of said table, and the lip being bent outwardly and adapted to contact only with the forward end of 65 said table, for the purpose described. 65

In testimony whereof, I hereunto affix my signature, this the 5th day of January, A. D. 1921.

TANNY C. GUSEMAN.
